(57) **CLAIM**

The ornamental design for a watch, as shown and described.

DESCRIPTION

FIG. 1 is a perspective view of the front and interior of a partially open watch showing my new design according to a first embodiment;

FIG. 2 is a front elevational view of the watch, the watch being completely open;

FIG. 3 is a rear elevational view thereof;

FIG. 4 is a side elevational view of one side thereof;

FIG. 5 is a side elevational view of the opposite side thereof;

FIG. 6 is an end elevational view of one end thereof; and,

FIG. 7 is an end elevational view of the opposite end thereof.
